UNITED STATES PATENT OFFICE

WALTER A. SMITH, OF FREEPORT, ILLINOIS, ASSIGNOR TO STOVER MANUFACTURING
& ENGINE CO., OF FREEPORT, ILLINOIS, A CORPORATION OF ILLINOIS

METHOD OF AND MACHINE FOR MAKING ONE-PIECE MOP HEADS

Application filed November 7, 1928. Serial No. 317,828.

This invention relates to the art of sheet metal working, and more particularly to the forming of sheet metal blanks cut to shape between blanking dies. In the present instance the invention is concerned with the quantity production of one-piece sheet metal mop heads of the kind shown in my co-pending application, Serial No. 283,153, filed June 6, 1928.

10 Mop heads were at one time made in the form of castings, but for many years have been made of sheet metal for better serviceability. The sheet metal mop heads were first of multi-part construction with the parts riveted or otherwise suitably fastened together, but they were found to be objectionable for various reasons, and there has, therefore, been a demand for a serviceable one-piece head. A few different forms of one-piece heads appeared on the market but apparently they left much to be desired, and were furthermore a difficult proposition to manufacture, requiring in addition to the blanking operation, a series of forming or bending operations.

20 The great amount of handling thereby necessitated discouraged quantity production and involved a high labor cost. Moreover, the product was bound to lack uniformity because of the inability to place the work accurately in the dies by hand, especially with quantity production as the objective, and, of course, a certain percentage would have to be scrapped on failing to pass inspection, the necessity for repeated inspections being likewise an objectionable feature from the standpoint of cost of production. Then, too, there has to be considered the fact that the handling of irregularly shaped pieces, besides being slow, is bound to be dangerous, and injuries

30 frequently resulted.

The principal object of my invention is to provide a new and improved method and machine for the quantity production of sheet metal parts of the kind referred to, or any parts the characteristics of which would

otherwise require successive forming operations, and contemplates the use of special double-acting dies in an otherwise conventional punch press cooperating in such manner that the sheet metal blanks are arranged to be fed one at a time to the press and formed up completely in one operation of said dies as distinguished from the two or more separate operations heretofore required.

Still another object of the invention has reference to the manufacture of sheet metal parts of the kind referred to which does away with the necessity for drawing the metal, where to do so would mean objectionable weakening of the part, if not its rejection at the time of inspection, so that the durability of the part is not sacrificed in the speedy production thereof, but instead is greatly improved over what was heretofore obtained.

Still other objects, not enumerated at this point, will appear in the course of the following detailed description, in which reference is made to the accompanying drawings, wherein—

Figure 1 is a side view on a small scale of a punch press modified in accordance with my invention for double-actuation of the dies in a predetermined desired timed relation;

Fig. 2 is a fragmentary central vertical section of the machine on a larger scale;

Fig. 3 is a transverse sectional detail on the line 3—3 of Fig. 2;

Figs. 4 and 5 are respectively a plan view of the lower die with its holder and feeding guides, and an underside plan view of the upper die and its holder;

Figs. 6, 7 and 8 are enlarged fragmentary sectional details on the lines 6—6, 7—7, and 8—8 of Fig. 4 respectively, Fig. 9 being a view similar to Fig. 8, showing the auxiliary lower die at the upper end of its stroke to complete the forming operation;

Fig. 10 is a composite view showing in full lines the completely formed mop head, and

in dotted lines the blank from which the same is formed; and

Fig. 11 is a perspective view of the mop head to give a better idea of the shape thereof.

5 The same reference numerals are applied to corresponding parts throughout the views.

Before proceeding with a description of my improved machine and method of making the mop head, reference should be made to

10 Figs. 10 and 11 for an understanding of the principal features or characteristics thereof. As described in my application referred to above, the mop head, or mop head jaw as it is sometimes called, designated by the reference

15 numeral 12, is formed from one piece of sheet metal, originally in the form of a generally triangular-shaped blank represented at B, No. 18 gauge sheet metal being found satisfactory for the purpose. The head has a

20 slightly tapered socket formed therein to receive the lower end of the handle spindle, said socket comprising oppositely bent semi-circular but slightly tapered strap portions 13 and 14 and lower semi-cylindrical but slightly

25 tapered socket portion 15. The strap portion 14 is defined by shearing of the metal of the blank along substantially parallel lines 16 and 17, and this portion, as well as the portions 13 and 15, are produced mainly by a

30 forming operation. The strap portions, of course, are integral with the rest of the head at their both ends, and the socket portion 15 is integral therewith on the three sides thereof. The lower end of the socket portion 15,

35 which is formed by drawing, as will presently appear, provides an end thrust seat for the handle spindle which aids in establishing a firm and solid connection between the handle spindle and the head. A hole 18 is pierced

40 in the blank B in the blanking operation so that a nail or other fastener can be used to fasten the head to the handle spindle. The head constitutes the stationary jaw with which the usual form of bail is arranged to

45 cooperate to hold the mop or swab. A central, transverse, angular flange 19 is formed by bending a marginal portion of the lower edge of the blank B along the line 20 between notches 21. Two end flanges 22 are bent in

50 angular relation to the plane of the rest of the head in the opposite direction from the central flange 19 along lines 23 between the notches 21 and notches 24 formed in each end of the head. The flange 19 and flanges

55 22 form a bail-receiving groove in addition to affording reinforcement of the lower end of the head from end to end thereof such that there is little danger of the head being bent to the extent of throwing the groove out of

60 alignment with the bail. The bail is received in the notches 24 between the ends of the flanges 22 and guide lugs 25 formed at the opposite ends of the head, the latter being struck into offset relation with the plane

65 of the rest of the head along the lines 26 ex-

tending away from the notches 24 so that the bail received in the notches 24 has its cross piece in proper alignment with the groove formed by the divergence of the flanges 19 and 22. Ribs 27 are formed in the head to reinforce the same across the narrow end portions which might otherwise have a tendency to bend when the mop is subjected to rough treatment. So much for a description of the characteristics of the mop head, the making 75 of which the present invention is particularly concerned with. I will now proceed to a description of the method and machine for making the head.

Referring now to the other figures of the drawings, the punch press shown in Fig. 1 has a frame 28 rising from a base 29 inclined rearwardly at an angle of about thirty degrees to the vertical. The ram 30 of said press is reciprocable in guides 31 provided therefor in the frame 28. Rods 32, extending upwardly from the ram through guides 33 on the frame, have compression springs 34 cooperating therewith, normally tending to move the ram to retracted, raised position. A cam 35, fixed on cross shaft 36 mounted in bearings in the frame 28, cooperates with a roller 37 mounted on the ram 30, the cam riding on the periphery thereof whereby to communicate movement to the ram against the action of its springs 34 through a uniform stroke, at the lower end of which the ram is caused to pause throughout approximately ninety degrees rotation of the shaft 36 as determined by the dwell on the cam 35. The shaft 36 has a gear 38 arranged to be clutched therewith to turn the same in a clockwise direction, as indicated by the arrow in Fig. 1, the gear 38 being driven by a pinion 39 on a countershaft 40 driven in any suitable manner, as for example, by a pulley 41 mounted on said shaft. Another cam 42 is mounted on the shaft 36 and cooperates with a roller 42 mounted on a rocker arm 43, the cam operating on the periphery thereof. The arm 43 is pivoted at 44 on the frame 28 and has a pull rod 45 connected therewith and extending downwardly therefrom to the base 29 for connection with an arm 46 mounted on the end of a shaft 47 received in bearings in the base 29. Another arm 48 is mounted on the shaft 47 within the base 29 (see Fig. 2), the free end of which is formed for cooperation with an opening 49 in a slide 50 reciprocable in ways 51 on a bracket 52 mounted in the base 29. The slide 50, the purpose for which will presently appear, is thus arranged to be reciprocated in timed relation with the ram 30. The angular relationship of the cam 42 with reference to the cam 35, which best appears in Fig. 1, is such that the reciprocation of the ram 50 occurs near the end of the pause of the ram on the lower end of its stroke. As will presently appear, the ram 30 has brought the main dies together and 130

completed the major portion of the forming operation before the slide 50 comes into play to operate auxiliary dies to finish the forming operation, the timed relationship in the 5 operation of said dies being of great importance from the standpoint of avoiding the slightest possibility of fracturing the blank at any point by drawing thereof; the mop head being produced practically entirely by 10 a forming operation so as to retain as nearly as possible at all points the same thickness of stock and thus maintain the desired strength and serviceability.

There are two main dies 53 and 54, these 15 being hereinafter referred to respectively as the upper and lower dies, and two auxiliary dies 55. The upper and lower dies are sectional or built-up in conformity with the usual practice, although they are, for purposes of simplicity, shown herein as being each made in one piece. The upper die 53 is mounted in a die holder 56 on the ram 30, and the lower die 54 is mounted in a die holder 57 on the bolster plate 58. The usual 20 guide pins, extending from one die holder to the other and serving to insure accurate register of the die impressions, are shown at 59. The blanks B are fed to the press one by one from in front thereof between guides 60. 25 The blanks slide down inclined tracks 61 provided on a table 62 carried by the die holder 57. Adjustable stops 63 limit the movement of the blank by engagement at each end thereof when the blank arrives at a position over 30 the lower die 54. The stops 63 thereby also line up the blank with the dies. Auxiliary 35 guides 64 at either side of the die 54 cause the blank to be shifted laterally one way or the other into precise register with the dies, 40 and it will be noted that the guides 64 are set at a slight angle so they converge rearwardly, and if the blank is off side either way, the end thereof will ride on the guide 64 and the blank will be sure to be trued up. In Fig. 2 a blank 45 is shown in dotted lines sliding on the tracks 61, and another blank B is shown in dotted lines over the lower die in engagement with the stop 63, but it will be understood that this is merely for the purpose of illustration; 50 only one blank will be fed to the press at a time. It is also with a view to better illustration that I have resorted to the showing in dotted lines of a formed-up blank B in the act of being ejected from the upper die 53. When 55 the blank comes into engagement with the stops 63, it rests in a position parallel with the lower die 54 on pins 65, of which there are four, slidably received in holes 66 in the lower die 54 and having compression springs 60 67 serving normally to hold the same extended a definite amount determined by the engagement of the heads 68 on said pins with the annular shoulders 69 defining the ends of the bores 70 in which the springs 67 and the 65 headed ends of said pins are received. The

pins 65 will, of course, yield when the dies 53 and 54 are brought together (see Fig. 7) but serve to keep the blank in position especially at the beginning of the forming operation, and subsequently serve to eject the blank from the lower die 54. Other 70 ejector pins 71 are slidably received in holes 72 in the upper die 53 and normally project from the upper die impression as shown in Fig. 2. These pins are not, however, arranged to be held extended by springs like the pins 65, but are mounted on a head 73 (see Fig. 2) which, when the ram 30 is retracted, is arranged to be struck by a lever 74 to move the pins 72 positively to extended 75 position. The lever 74 is pivoted on the ram at 75 and has one end thereof arranged to be engaged by a screw 76 mounted on a part 77 fixed on the frame 28. The frictional fit of the pins 71 in their holes 72 and also the 80 tendency for the formed-up blank to stick in the upper die impression is enough to prevent the ejection of the blank from the upper die 53 before the ram 30 arrives at or near its fully retracted position. An air 85 nozzle 78, communicating with a compressed air line, has a valve (not shown) arranged to be opened on each up stroke of the ram 30 so that a blast of air serves to throw the finished blank to the rear the moment it is 90 ejected from the upper die impression. A suitable receptacle at the rear of the press is placed to catch the finished blanks as they are thrown out one by one.

Referring now more particularly to Figs. 100 4 to 9, it will be observed that the lower die 54 has a substantially semi-cylindrical but slightly tapered projection 79 at its approximate center and that the upper die 53 has a recess 80 in register therewith to receive the 105 same, the projection 79 extending substantially above the plane of the rest of the die 54 and the recess 80 of the die 53 being, of course, of corresponding depth. Fore and aft with respect to the recess 80, and on the 110 same median line therewith, the die 53 has a pair of substantially cylindrical but also slightly tapered projections 81 and 82, the mating die 54 being provided with recesses 83 and 84 to receive the same. Thus, co-operating shearing edges are provided at a and b on the dies 53 and 54 respectively to cut the blank B along the lines 16 and 17 so as to form the strap portion 14 on the projection 79 and to form the strap portion 13 on the projection 81. The outer end of the projection 82 is beveled off as shown at 85, and it is partly by the projection 82 and partly by its beveled off end 85 that the substantially semi-cylindrical but slightly tapered socket 15 is formed in the blank. Obviously, the blank is held between the pins 65 and 71 during the shearing along the lines 16 and 17 and during the first stages of the forming of the strap and socket portions re- 120 125 130

ferred to. The holding of the blank by the pins does not amount to a positive gripping, as should be evident from the foregoing description, hence, the stock is perfectly free to flow, as it were, or, more specifically, be gathered in from both sides of the blank toward the central butt portion where the strap and socket portions are being formed and where, of course, additional stock is needed, since the fashioning of the blank does not rely upon drawing of the stock. Thus, the extra width of stock provided in the butt portion of the blank, as appears in dotted lines in Fig. 10, is taken up or absorbed in the forming of the strap and socket portions 13-15, and this gathering in of the stock brings into line the ends of the blank which theretofore extended in diverging relationship, as also appears from the dotted line showing of the blank in connection with the full line showing of the completed mop head in Fig. 10. There is substantially no drawing of the stock except only to a very small extent in the closed end 25 of the socket portion 15. The latter point is evident in Fig. 6 and also in Fig. 10 where it appears how the stock is drawn slightly from the line of cut 17 in the forming of the socket 15. Slightly previous to the completion 30 of the forming of the strap and socket portions 13-15, the blank encounters a ridge 86 provided on the lower die 54 in transverse relation to and defining the end of the recess 84, and arranged to cooperate 35 with this ridge is a groove 87 formed in the upper die 53 just in front of the projection 82 so that the flange 19 is formed on the edge of the blank. Now, it should be evident that the gathering in of the stock has occurred before the forming of the flange, so 40 that there is no danger of the flange tending to be distorted because of drawing of the stock subsequent to the forming thereof; all of the stock needed, or substantially all, has been gathered in before the forming of the flange 19 commenced. At either side of the socket portion 15 where the blank is left perfectly flat, the balance of the flange 19 is formed between the chamfered portion 86' 45 of the lower die 54, which is a continuation of the outer face of the ridge 86, and a surface 87' which is an extension of the outer side of the groove 87 (see Fig. 7). Simultaneously with the forming of the flange 19, the guide lugs 25 are formed by somewhat 50 similarly shaped die projections 88 on the upper die 53 and recesses 89 on the lower die 54 (see Figs. 4 and 5), and it will, of course, be evident, since these guide lugs are not 55 formed until the forming of the strap and socket portions 13-15 has been practically completed, that there is no drawing of the stock and consequently no danger of fracture thereof. All of the forming of the blank, or at least the major portion thereof,

it will be seen, is downwardly and yet with the mating die impressions so arranged that no two parts are permitted to grip the blank therebetween before the substantial completion of the forming of the strap and socket portions. There is, however, a slight drawing of the stock to form the ribs 27, the lower die 54 having correspondingly shaped projections 90 thereon for forming the ribs 27 by drawing of the metal up into registering recesses 91 formed in the upper die 53. When the dies 53 and 54 have been brought together as shown in Figs. 7 to 9, to within a clearance equivalent to the stock thickness, it will be evident that the mop head has 60 been formed completely with the only exception of the two flanges 22 which have to be bent in the opposite direction from the flange 19. The reasons why it is not feasible to form the flanges 22 in the same way and at the same time as the flange 19 are, first, that the projections and recesses that would have to be provided on the upper and lower dies to form the flanges 22, similar to the projections and recesses provided on the dies for the forming of the flange 19, would commence to grip the blank at its opposite ends so that the stock would not be free to become gathered in for the forming of the strap and socket portions 13-15, experience 65 having shown that the blank would fracture under such circumstances at the ends of the straps 13 and 14 and at the sides of the socket portion 15; and, second, that the co-operative projections and recesses that would have to be provided on the upper and lower dies to form the flanges 22 would serve to bend the blank upwardly at one side of the notches 21, while the projections and recesses 86-87 and 86'-87' for forming the flange 19 would be tending to bend the blank downwardly at the other side of the notches 21, while the body of the blank itself would be entirely without support, so that there would be nothing to prevent the tearing of the blank at each of the notches; the action would be almost equivalent to a shearing action but more like a tearing action. It is for these reasons that I prefer to complete the forming of the blank with the exception 70 of the flanges 22 in the first part of the forming operation and then, while the blank is firmly held between the upper and lower dies by all parts excepting the portions from which the flanges 22 are formed, operating an auxiliary set of dies at the end of the forming operation to complete the mop head, as will now be described.

The auxiliary dies are those shown at 55. These dies are conformed with projections 92 arranged to cooperate with recesses 93 provided on the upper die 53, as best appears in Figs. 8 and 9, so that when the auxiliary dies 55 are forced up against the upper die 53 the flanges 22 are formed substantially 95

as shown in Fig. 9. Obviously, there is no tendency to tear the blank inasmuch as the same is firmly held between the upper and lower dies 53 and 54 on both sides of the notches 21. Furthermore, if, as a result of the forming of the strap and socket portions 13—15, there is any tendency for a "come-back" of the stock at the ends of the blank, the forming of the flanges 22 will serve to positively prevent any such distortion of the mop head after it leaves the dies. The flanges 22 furthermore constitute a reinforcement such that there is little danger of the ends of the mop head getting bent. The dies 55 are slideable in notches 94 provided therefor in the ends of the lower die 54 and through holes 95 and 96 provided respectively in the die holder 57 and bolster plate 58. The lower ends of the dies 55 are fastened to a cross head 97, which in turn is adjustably secured to the slide 50 by means of bolt 98. Adjustment of the set screw 99 adjusts the projection of the dies 55 relative to the lower die 54. It has been pointed out above that the operation of the slide 50 occurs near the end of the pause of the ram 30 at the lower end of the stroke of the latter. Since the auxiliary dies 55 are operated by the slide 50, it follows that the dies 55 perform their part of the forming operation at the end of the forming operation performed by the upper and lower dies 53 and 54 and just before the same are parted.

It is believed the foregoing description conveys a sufficiently clear understanding of my invention so that anyone skilled in the art to which the invention relates will readily appreciate the various advantages which have been enumerated. So far as the machine is concerned, it should be evident that the same is capable of a great deal of modification, and, on the other hand, so far as the method is concerned, it should be evident that the practicing thereof is not limited to a machine of the specific kind shown nor is it limited to the production of the specific product described. All legitimate modifications and adaptations are intended to be covered in the appended claims.

I claim:

1. The method of making a sheet metal article, like a mop head, having a socket portion integral with the rest of the body portion, which comprises the following steps, first, cutting a generally triangular-shaped sheet metal blank, the base portion of which is destined to be formed to a certain shape, and the apex portion of which is destined to have the socket formed therein, the latter portion being provided of ample width to furnish sufficient stock to permit forming of the socket substantially without any drawing, second, striking the blank between dies to form oppositely directed strap portions to provide a socket, without drawing but by

using the additional stock in the apex portion, and third, thereafter forming the base portion to the desired shape.

2. The method of making a sheet metal article, like a mop head, having a socket portion integral with the rest of the body portion, which comprises the following steps, first, cutting a generally triangular-shaped sheet metal blank, the base portion of which is destined to be formed eventually to a certain shape but is originally cut to an irregular shape, and the apex portion of which is destined to have the socket formed therein, the latter portion being provided of ample width to furnish sufficient stock to permit forming of the socket substantially without any drawing, second, striking the blank between dies to form oppositely directed strap portions to provide a socket, without drawing but by using the extra stock in the apex portion, the base portion in said second step being brought to regular shape ready for forming, and, third, forming the base portion to the desired shape.

3. The method of making a sheet metal article, like a mop head, which comprises the following steps, first, cutting a sheet metal blank, one portion of which is destined to have a socket formed therein and having extra stock provided therein for the purpose, and a second portion of which is to be formed to a certain shape, second, forming a socket portion in the first portion between dies and without drawing of the stock but by using the extra stock provided in said portion for the purpose, and, third, forming the second portion of the blank to the desired shape after the substantial completion of the forming of the socket.

4. The method of making a sheet metal article, like a mop head, which comprises the following steps, first, cutting a sheet metal blank, one portion of which is destined to have a socket formed therein and having extra stock provided therein for the purpose, and a second portion of which is to be formed to a certain shape and is originally cut to an irregular shape, second, forming a socket portion in the first portion between dies and without drawing of the stock but by using the extra stock provided in said portion for the purpose, the second portion being thereby simultaneously brought to a regular shape ready for the forming operation to be performed thereon, and, third, forming the second portion of the blank to the desired shape.

5. The method of making a one-piece sheet metal article, like a mop head, which comprises the following steps, first, cutting a generally triangular-shaped blank of sheet metal, the apex portion of the blank being destined to have a socket formed therein and being provided of ample width to furnish sufficient stock for the socket substantially

without any drawing, and the base portion of said blank being destined to have aligned jaw portions formed thereon but being originally cut with the two ends thereof diverging downwardly with reference to one another, second, subjecting the blank to a forming operation between dies so that a socket is provided by oppositely bent strap portions substantially without any drawing of the stock of the blank but by using the stock in the apex portion, the ends of the base portion of the blank being thereby also brought into substantial alignment, and third, forming aligned jaw portions on the base portion of the blank.

6. The method of making a one-piece sheet metal mop head, which comprises the following steps, first, cutting a generally triangular-shaped blank of sheet metal destined to be 10 a mop head, the apex portion of the blank being destined to have a mop handle socket formed therein and being provided of ample width to furnish sufficient stock for the socket substantially without any drawing, and the 15 base portion of said blank being destined to have aligned mop jaws formed thereon but being originally cut with the two ends thereof diverging downwardly with reference to one another, second, subjecting the blank to 20 a cutting and forming operation between dies so that a plurality of oppositely bent strap portions are formed intermediate the ends of the blank at the apex thereof and simultaneously a socket portion which, together with the strap portions, constitutes a 25 mop handle socket, all of the said portions being formed substantially without any drawing of the stock, the stock being gathered in from adjacent portions of the blank to form 30 the stock and said forming operation being attended by the straightening of the base portion of the blank, and third, forming aligned 35 jaw portions on the base portion of the blank after the substantial completion of the forming of said mop handle socket.

7. The method of making a one-piece sheet metal mop head which comprises the following steps, first, cutting a generally triangular-shaped blank of sheet metal destined to be a 40 mop head, the apex portion of the blank being destined to have a mop handle socket formed therein and being provided of ample width to furnish sufficient stock for the socket substantially without any drawing and the 45 base portion of said blank being destined to have aligned bail-receiving jaws formed thereon but being originally cut with the two ends thereof diverging downwardly with reference to one another, second, subjecting the blank to a forming operation to provide 50 a socket using the stock in the apex portion and substantially without any drawing, the ends of the base portion of the blank in the socket forming operation being brought into 55 substantial alignment, and third, forming

aligned bail-receiving jaws on the base portion of the blank.

8. The method of making a one-piece sheet metal mop head which comprises the following steps, first, cutting a generally triangular-shaped blank of sheet metal destined to be a mop head, the apex portion of the blank being destined to have a mop handle socket formed therein and being provided of ample width to furnish sufficient stock for the socket substantially without any drawing and the base portion of said blank being destined to have aligned bail-receiving jaws formed thereon but being originally cut with the two ends thereof diverging downwardly with reference to one another, second, subjecting the blank to a forming operation to provide a socket using the stock in the apex portion and substantially without any drawing, the ends of the base portion of the blank in the socket forming operation being brought into substantial alignment, third, forming an intermediate part of the base portion of the blank upon the substantial completion of the socket forming operation with a flange bent into angular relation to the rest of the blank to form part of the bail-receiving jaws, and fourth, after the completion of the above forming operations forming the ends of the base portion of the blank with flanges bent into angular relation with the rest of the blank in the opposite direction from the intermediate flange to form the rest of the bail-receiving jaws.

9. The method as set forth in claim 8, wherein the blank is formed with notches to define the ends of the intermediate flange on the base portion thereof, and which consists further in forming in the blank, at the same time that the intermediate flange is formed, a reenforcing rib at each side of the socket extending transversely with reference to said notches.

10. The method of making a mop head which comprises the following steps, first, cutting a generally triangular-shaped blank of sheet metal, second, forming the blank with a flange on the base portion of the blank extending in angular relation thereto in one direction to constitute part of a bail-receiving groove, and third, forming another flange on the base portion of the blank in angular relation thereto and oppositely directed as regards the first flange whereby to constitute the rest of a bail-receiving groove.

11. The method of making a mop head which comprises the following steps, first, cutting a generally triangular-shaped blank of sheet metal, second, forming the intermediate part of the base portion of the blank with a flange bent in angular relation to the blank to form part of a bail-receiving groove, and third, forming the opposite end parts of the base portion of the blank with flanges bent in the opposite direction from the first flange

into angular relation with the blank to form the complementary parts of the bail-receiving groove.

12. The method of making a sheet metal mop head which comprises, first, cutting a generally triangular-shaped blank of sheet metal having notches in the base portion to define the ends of a plurality of sections destined to form bail-receiving groove flanges, second, forming the blank between dies so that a part of said sections are bent in one direction into angular relation with the rest of the blank, and third, while the blank is held between the dies, so as not to tear at the notches, forming the rest of the sections so they are bent in the opposite direction into angular relation with the rest of the blank.

13. The method of making a one-piece sheet metal mop head which comprises the following steps, first, cutting a generally triangular-shaped blank of sheet metal with notches in opposite ends of the base portion destined to receive a bail and with spaced notches in the base portion defining the ends of marginal sections destined to form bail-receiving groove flanges, the apex portion of the blank being provided of ample width to furnish sufficient stock for a handle receiving socket and the base portion of said blank being formed with the two ends thereof diverging downwardly with reference to one another, second, subjecting the blank to a shearing and forming operation between dies so that a socket is formed in the apex portion by oppositely bent portions of said blank formed substantially without any drawing of the stock of the blank but by using the extra stock allowed in the apex portion, the ends of the base portion in said operation being brought into substantial alignment, third, forming a part of the marginal sections of the base portion of the blank bent into angular relation to form part of a bail-receiving groove and substantially simultaneously forming the ends of the blank on one side of the end notches to form part of a pair of bail-receiving guides, and fourth, forming the rest of the marginal sections of the base portion of the blank bent into angular relation with the rest of the blank in the opposite direction from that of step three to form the complementary part of the bail-receiving groove and likewise the rest of the bail-receiving guides.

14. The method set forth in claim 13 consisting further in forming reinforcing ribs in the blank at opposite sides of the socket and in transverse relation with the notches defining the marginal sections of the base portion of the blank.

15. In a machine of the character described, the combination with a base, a frame rising therefrom, and a ram reciprocable in guides therein, of a lower stationary die, an upper movable die mounted on the ram, said dies having mating projections and recesses for

performing an operation on a sheet metal blank placed therebetween, an auxiliary die operating in a guide opening provided in the lower die, a slide mounted in guides in the base serving to operate said auxiliary die, a main rotary cam for operating the ram, said cam having a dwell thereon providing for a pause of the upper die on the lower end of its stroke, an auxiliary cam turning with the main cam in angularly retarded relation therewith, and linkage operated by the auxiliary cam for communicating movement to the slide in said case whereby to operate the auxiliary cam during the pause of the main cam on the lower end of its stroke.

16. In a punch press comprising a frame and a ram reciprocable in the guides therein, a lower stationary die, an upper movable die mounted on the ram for movement toward and away from the stationary die, said dies having mating projections and recesses, an ejector pin operating in a guide opening provided in the upper die, said pin being arranged to be forced to retracted position when the dies are brought together and the work piece being arranged normally to stick in the upper die when the latter is retracted from the lower die, and means for automatically moving the ejector pin to extended position in the retracting movement of said upper die.

17. A machine as set forth in claim 16 wherein the last mentioned means comprises a lever pivotally mounted on the ram and having operative engagement with the pin, and a stop arranged to be engaged by a part of said lever at a certain point in the travel of said ram in the retracting movement thereof arranged to move the lever and thereby move the pin to extended position so as to eject the work piece.

18. The method of making a mop head which comprises the following steps, first, cutting a generally triangular-shaped blank of sheet metal with notches provided in the base portion of the triangle, second, forming the blank with a flange on the base portion between the notches and extending at an angle to the plane of the blank in one direction to provide part of a bail-receiving groove, third, forming other flanges on the base portion on the other sides of the notches in angular relation to the plane of the blank in the opposite direction from the first flange to constitute the rest of a bail-receiving groove, and forming reinforcing ribs in the blank adjacent to and transverse with reference to the notches.

19. The method of making a sheet metal article, such as a mop head, which comprises the following steps, first, cutting a sheet metal blank of approximately the outlines of the article, second, producing abnormal sized projections on said blank by a forming operation, using the available fullness of ma-

- material in the blank, and third, suitably fash-
ioning the rest of the blank with the other
desired projections of normal size.
20. The method of making a sheet metal
article, such as a mop head, which comprises
the following steps, first, cutting a sheet
metal blank of approximately the outlines
of the article, second, producing abnormal
sized projections on said blank by forming
10 as distinguished from drawing, using the
available fullness of material in the blank,
and third, suitably fashioning the rest of
the blank with the other desired projections
of normal size, partly by drawing.
- 15 21. In a machine of the character de-
scribed, the combination with a base, a frame
rising therefrom, and a ram reciprocable in
guides therein, of a stationary die, a mov-
able die mounted on the ram, said dies hav-
20 ing mating projections and recesses for per-
forming an operation on a sheet metal blank
placed therebetween, an auxiliary die op-
erating in a guide opening provided in one of
the dies, a slide mounted in guides in the base
25 serving to operate said auxiliary die, a main
rotary cam for operating the ram, said cam
having a dwell thereon providing for a pause
of the movable die at the end of its stroke, an
auxiliary cam turning with the main cam in
30 angularly retarded relation therewith, and
linkage operated by the auxiliary cam for
communicating movement to the slide in said
case whereby to operate the auxiliary cam
during the pause of the main cam.
- 35 22. In a punch press comprising a frame
and a ram reciprocable in guides therein, a
stationary die, a movable die mounted on the
ram for movement toward and away from
the stationary die, said dies having mating
40 projections and recesses, an ejector pin op-
erating in a guide opening provided in the
movable die, said pin being arranged to be
forced to retracted position when the dies are
brought together and the work piece being
45 arranged normally to stick in the movable die
when the latter is retracted from the other
die, and means for automatically moving the
ejector pin to extended position in the re-
tracting movement of said movable die.
- 50 23. In a punch press comprising a frame
and a ram reciprocable in guides therein, a
stationary die, a movable die mounted on the
ram for movement toward and away from
the stationary die, said dies having
55 mating projections and recesses, an ejector pin
operating in a guide opening provided in the
one die, said pin being arranged to be
forced to retracted position when the dies are
brought together and the work piece being
60 arranged normally to stick in the die
equipped with said pin when the dies are
parted, and means for automatically moving
the ejector pin to extended position in the re-
tracting movement of said movable die.
- 65 24. A machine as set forth in claim 23

wherein the last mentioned means comprises
a lever pivotally mounted on the ram and
having operative engagement with the pin,
and a stop arranged to be engaged by a part
of said lever at a certain point in the travel of
70 said ram in the retracting movement thereof
arranged to move the lever and thereby move
the pin to extended position so as to eject the
work piece.

In witness of the foregoing I affix my sig- 75
nature.

WALTER A. SMITH.
